(57) **CLAIM**

The ornamental design for a travel bottle, as shown and described.

DESCRIPTION

FIG. 1 is a front, top perspective view of a travel bottle, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is an enlarged top plan view thereof;
FIG. 8 is an enlarged bottom plan view thereof; and,
FIG. 9 is an enlarged view of detail "9" identified in FIG. 2. The dashed broken lines in the figures illustrate portions of the travel bottle that form no part of the claimed design. The dash-dot-dash broken lines in FIGS. 2 and 9 depict the bounds of the enlarged views and form no part of the claimed design. The dash-dot-dash broken line in FIG. 8 defines the boundary of the claimed design and forms no part of the claimed design.
